(57) **CLAIM**

The ornamental design for a utensil handle, as shown and described.

DESCRIPTION

FIG. 1 is a perspective view of a utensil handle with a stand in a closed configuration in accordance with the present design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a perspective view of the utensil handle with a stand in an open configuration in accordance with the present design.

The broken lines shown in the drawings illustrate portions of the utensil handle that form no part of the claimed design.

1 Claim, 6 Drawing Sheets
